DOMESTIC LAUNDRY EQUIPMENT

Filed March 15, 1930

UNITED STATES PATENT OFFICE

THOMAS WILLIAM CHADBURN, OF TORONTO, ONTARIO, CANADA

DOMESTIC LAUNDRY EQUIPMENT

Application filed March 15, 1930. Serial No. 436,196.

My invention relates to improvements in domestic laundry equipment, and the object of the invention is to incorporate in a laundry tub structure including a central support, 5 pedestal and a plurality of laundry tubs mounted therearound, means coating and forming a unitary structure therewith for performing the washing and wringing operations in any tub desired, and it consists essentially of the arrangement and construction of parts all as hereinafter more particularly explained.

Fig. 1 is a perspective view of my domestic equipment.

15 Fig. 2 is a detail sectional view through the gear box showing the means for driving the washing and wringing mechanism.

Fig. 3 is a sectional plan view on line 3—3 Fig. 2.

20 Fig. 4 is an enlarged detail of the detachable connection between the divided members of the washing paddle shaft.

Fig. 5 is a detail of the means for releasably locking the clutch lever in its adjusted position.

Fig. 6 is a sectional detail of the paddle 16 taken on line 6—6 Fig. 1.

Fig. 7 is a sectional detail of the paddle 16 taken on line 7—7 Fig. 1.

30 In the drawings like characters of reference indicate corresponding parts in each figure.

1 is the central pedestal provided with a sleeve 2 which is supported thereon to revolve therearound, such sleeve being provided with upper and lower flanges 2^x and 2° between which a plurality of tub supporting brackets 3 are swingably mounted as indicated at 4. 35 5 and 6 are hot and cold water supply pipes which extend up through the central pedestal 1 so as to feed the water into any one of the tubs 7 carried on the brackets 3.

I do not describe the above structure further in detail as it does not form part of the present invention and is only described to make clear my improvements.

8 and 9 are bracket supports forming part of the central pedestal 1 and preferably located at diametrically opposite points. To 40 the supports 8 and 9 are secured bracket mem-

bers 10 and 11. 12 is a wringer to which the flange 13 of the bracket 11 is suitably secured, the portion 14 forming a gear case for the wringer gears. 15 is a cover which is so constructed as to fit any one of the tubs 7. 16 55 is a washing paddle which is formed somewhat in the shape of a propeller blade, the main body of the propeller inclining forward at an angle as indicated at 16^x, the upper edge being offset towards a horizontal direction to 60 form a lip as indicated at 16°.

The paddle 16 is carried upon a vertical shaft 17 which is turnably mounted in the cover 15 supported therein by the collar 17^x which is set screwed or otherwise suitably 65 secured to the shaft member 17. 17° is the upper member of the paddle shaft which is detachably connected to the member 17 by means of a sleeve 18 which is provided with bayonet slots 19 into which diametrically 70 opposite pins 20 extend from the shaft 17°. 21 are open ended slots extending from the lower end of the sleeve into which diametrically opposite pins 22 extend.

It will, therefore, be seen that all it is 75 necessary to do when it is desired to detach the paddle and the lower shaft member 17 from the upper shaft member 17° is to raise the sleeve vertically until the pins 22 are carried clear of the slots 21 and the pins 20 into 80 the horizontal portions of the bayonet slots 19.

The shaft member 17, paddle 16 and cover 15 may then be lifted clear of the laundry tub and placed in any one of the other tubs desired and the operating mechanism connected 85 thereto as will hereinafter appear.

23 is a rectangular gear case provided at its upper end with an outwardly extending arm 23^x provided with a cover 23°. The gear case 23 is formed integral with the bracket member 10 secured as above described to the bracket support 8. 24 is a supplemental bracket carried by the gear case 23 and upon which is mounted a driving motor 25 provided with a drive shaft 26. 27 is a worm secured to the shaft 26. 28 is a vertical shaft extending centrally through an orifice 29 formed in the cover 23° over which extends a housing 30 having a central orifice 31 10°

through which the shaft 28 also extends.

32 is a collar secured to the upper end of a shaft 28, such collar resting on the top of the housing 30 to support the shaft 28 vertically. 33 is an intermediate bearing through which the shaft also extends. 34 is a worm gear secured to the shaft 28 and meshing with the worm 27. 35 is a gear freely mounted upon the shaft 28 intermediate of its length and provided on its upper face with clutch projections 36. 37 is a clutch sleeve connected to the shaft 28 by a feather key 38*. The lower end of the sleeve 37 is provided with clutch projections 37* adapted to engage the clutch projections 36.

38 is a rock shaft journalled in the walls of the housing 30 upon which is mounted a fork 39 operated by a lever 40 to raise and lower the clutch sleeve 37 as desired to engage or disengage the gear 35 with the shaft 28.

41 is a stud shaft carried in the casing extension 23* upon which is mounted a gear 42 meshing with the gear 35. 43 is a crank wheel secured to the upper end of the member 17* 25 of the paddle shaft. 44 is a link bar pivotally connected at one end upon the crank pin 43 of the crank wheel 43 and at its opposite end to a crank pin 43* carried by the gear 42. 45 is a shaft journalled in opposite walls of the gear case 23, the shaft extending diametrically through the pedestal 1 and through the lower portion of the bracket 10. The shaft 45 is detachably connected to the driving shaft 12* of the wringer 12 by a sleeve 46 which is provided at its ends with open ended slots 46* into which diametric pins 47 and 48 extend.

49 is a bevelled gear which is secured to the shaft 28 beneath the worm gear 34. 50 and 51 are bevel gears secured to the shaft 45 and meshing with the gear 49 at diametrically opposite points. 52 is a clutch sleeve feather keyed to the shaft 45 and adapted to alternately engage the clutch projections extending from the gears 50 and 51. 53 is a rock shaft mounted in the walls of the gear case 53 at right angles to the shaft 45 and provided with a clutch sleeve operating arm 54. 55 is a clutch operating lever mounted on the pedestal 1 intermediate of its length and connected at its lower end by a link rod 56 to an operating arm 57 secured to the outer end of the shaft 53.

The lever 55 may be releasably secured in the neutral position or the forward driving or reverse positions by any suitable means desired such as a spring pressed pin 58 carried in the bracket 10 and engaging suitably positioned orifices 59 in the arc-shaped plate 60 carried by the lever 55. 61 is a heating element which is preferably electric and which is carried by the bracket 62 secured to the pedestal 1.

By this means the element may be positioned beneath any one of the tubs 7 by

swinging the tubs around the pedestal to a position over the element and thereby keeping the water contained in the tub at boiling temperature.

Having described the principal parts involved in my invention I will briefly describe the operation of the same.

The washing paddle 16 is inserted in any one of the tubs and the upper and lower members of the paddle shaft 17 and 17* connected by the sleeve 18. The circuit of the driving motor 25 is then closed driving the motor shaft 26 and by means of the worm 27 and worm gear 34 driving the vertical shaft 28.

If it is desired to perform the washing operation the clutch sleeve 37 is moved to the closed position by the lever 40 thereby engaging the gear 35 with the shaft 28 and driving the paddle shaft member 17* and 17 through the gear 42 meshing with the gear 35, the link bar 34 and crank wheel 43. If desired during the driving of the paddle shaft the shaft 45 may remain disconnected by means of the clutch lever 55 being set in the neutral position. By throwing the clutch lever 55 to one side or the other the gears 50 and 51 may be alternately engaged so as to drive the shaft 45 either in one direction or the other and thereby operate the rollers of the wringer 12 in one direction or the other as circumstances require.

If desired, of course, the wringer 12 may be operated and the washing apparatus thrown out of operation by means of the clutch lever 40.

From this description it will be seen that I have devised a very simple device which will be compact, forming unitary structure, which will enable the operator to perform all of the functions necessary during laundry operation, having all the required mechanisms close at hand so that it will be absolutely under control of the operator and thereby enabling such operator to perform the entire operation in a minimum amount of time and with a minimum amount of labour.

What I claim as my invention is:

In a domestic laundry equipment the combination with a main standard support, a tub and tub supporting bracket carried by the support, of a tub lid having a central orifice, a vertical bearing secured in the orifice, a lower shaft member extending through the bearing and having a paddle on its lower end, means for supporting the shaft from longitudinal downward movement in the bearing, a gear box carried by the main standard and having a vertical bearing therein in alignment with the aforesaid vertical bearing, an upper shaft member journalled in said bearing, a coupling detachably connecting the upper and lower shaft members, and means for driving the upper shaft member from a suitable driving source.

THOMAS WILLIAM CHADBURN.
